US00D823263S

(12) **United States Design Patent** (10) **Patent No.:** **US D823,263 S**
(45) **Date of Patent:** **** Jul. 17, 2018**

(54) **OUTLET PLATE**

(71) Applicant: **Keith Cyzen**, Glen Ellyn, IL (US)

(72) Inventor: **Keith Cyzen**, Glen Ellyn, IL (US)

(**) Term: **15 Years**

(21) Appl. No.: **29/619,126**

(22) Filed: **Sep. 27, 2017**

(51) **LOC (11) Cl.** **13-03**

(52) **U.S. Cl.**

USPC **D13/156**

(58) **Field of Classification Search**

USPC D13/110, 123, 133, 137.1, 139.1, 139.4, D13/152, 154, 155, 156, 158, 162, 164, D13/173, 177, 184; D8/349-351, 353; 174/67, 66

CPC H01R 13/447; H01R 13/6395; H01R 13/639; H01R 13/6397

(57) **CLAIM**

The ornamental design for an outlet plate, as shown and described.

DESCRIPTION

FIG. 1 is a perspective view showing a new design for an outlet plate;

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a bottom view thereof.

The broken lines shown represent portions of the outlet plate that form no part of the claimed design.

1 Claim, 5 Drawing Sheets
